US00D634295S

(12) **United States Design Patent**
Turnbull et al.

(10) **Patent No.:** **US D634,295 S**
(45) **Date of Patent:** **** Mar. 15, 2011**

(54) **KEY EXTENSION MODULE FOR
TELEPHONE**

(75) Inventors: **Robert Turnbull**, Calgary (CA);
Alexander Feldman, Vancouver (CA);
David Render, Belleville (CA); **Robbie
Roberts**, Port Moody (CA)

(73) Assignee: **Avaya Inc.**, Basking Ridge, NJ (US)

(**) Term: **14 Years**

(21) Appl. No.: **29/352,171**

(22) Filed: **Dec. 17, 2009**

(57) **CLAIM**

The ornamental design of the key extension module for telephone, as shown and described.

DESCRIPTION

FIG. 1 is a top view of the key extension module according to the design;

FIG. 2 is a front view of the key extension module of FIG. 1; FIG. 3 is a right side view of the key extension module of FIG. 1;

FIG. 4 is a rear view of the key extension module of FIG. 1; and,

FIG. 5 is a top, front and left side perspective view of the key extension module of FIG. 1.

The broken lines showing portions of the key extension module for telephone are included for the purpose of illustrating environmental structure and form no part of the claimed design.

1 Claim, 3 Drawing Sheets
